UNITED STATES PATENT OFFICE

ERNESTO F. CIGLIA, OF SCARSDALE, AND LOUIS F. PELLETIER, OF EAST BRONX, NEW YORK, ASSIGNORS OF ONE-FOURTH TO WALTER W. IRWIN, OF NEW YORK, N. Y., AND ONE-FOURTH TO VICTOR von SCHLEGELL, OF WHITE PLAINS, NEW YORK

CARBURETOR

Application filed November 18, 1927. Serial No. 234,199.

This invention relates to vaporizing devices and more particularly to carburetors for vehicles using internal combustion engines though it is noted that the invention is not limited to such vehicles nor in some respects even to carburetors.

One of the primary objects of the invention is to provide novel means for carburetting air in a carburetor in such a manner that the air is uniformly and completely disposed through a body of atomized fuel as gasoline, for example.

Another principal object of the invention is to provide a plurality of concentrically arranged atomizing nozzles within the carburetor body in such a manner that air rushing by such nozzles is subjected to what we term a ripping or dividing action, resulting in a uniform and complete mixture of air and atomized gasoline.

Another object in our present construction relates to the means whereby, during idling position of the engine only a predetermined number of the atomizing nozzles are in operation to create sufficient volume of gasified fuel for idling conditions.

A further object resides in providing means whereby when the engine is operated to run at other than idling speeds, an additional sequence of nozzles are opened automatically by the aspiration of the engine pistons, during the intake stroke, whereby to furnish greater atomized fuel volumes synchronously with greater engine speeds.

A further object in our device is the provision of means whereby engine suction speeds automatically control on engine-suction operated Venturi shaped piston valve not only to cover or uncover jet nozzles, but also to control automatically the flow of fuel to the carburetor nozzles from a float chamber.

Still a further object in our construction is the provision of means in combination with said engine suction operated piston valve whereby said valve is controlled to operate to open the jet nozzles at predetermined rates of speed by the addition of a control means, herein disclosed as a dash pot; fuel supplied to the multiple nozzles being within said dash

pot and operating in such a manner that the said piston valve operates against a liquid cushion, thereby to prevent said engine suction valve means from being operated too rapidly to any desired ratios; thereby supplying fuel mixture to the engine in a controlled manner so that acceleration of the engine is gradually permitted; thereby giving an accelerated engine speed from idling to top speeds should the engine throttle suddenly be opened.

Other objects of the invention are to improve generally the simplicity and efficiency of such devices and to provide a device or apparatus of this kind which is economical, durable and reliable in operation, and economical to manufacture.

Still other objects of the invention will appear as the description proceeds; and while herein details of the invention are described and claimed, the invention is not limited to these, since many and various changes may be made without departing from the scope of the invention as claimed in the broader claims.

The inventive features for the accomplishment of these and other objects are shown herein in connection with an embodiment of a preferred form of our carburetor which, very briefly stated, includes a carburetor casing having therein a jet head disposed intermediate thereof and pointed toward the discharge end, and a piston valve in said casing, yieldably pressed toward the head and having a Venturi passage between said head and the discharge end.

In the drawings:

Fig. 1 is a side view of the carburetor.

Fig. 2 is an opposite side view thereof.

Fig. 3 is a sectional view of Fig. 2, taken on the medial plane therethrough.

Fig. 4 is a sectional view taken on the line 4-4, Fig. 2, looking in the direction of the arrows.

Fig. 5 is a diagonally sectional view taken across the mixing chamber of our construction from the side shown in Fig. 2, such sectional line not being shown.

Fig. 6 is an enlarged sectional view of the

gasoline control showing the movable needle in one position.

Fig. 7 is a similar view showing the gasoline feed control needle in the upward or full feed position.

Fig. 8 is a plan view of the multiple jet device with the upper main casing removed.

In Fig. 3, which is a complete sectional view of our apparatus, the carburetor comprises a main casing 1, mounting a fuel butterfly throttle valve 2 in the upper constricted portion thereof, said valve being mounted upon a shaft 3 and controlled by a lever arm 4, Fig. 1. The lever arm is made in the form of a split clamp held to the shaft 3 exteriorly of the carburetor by a locking screw 5. The clamp in addition to being provided with the lever arm 4 has a pair of offset stop arms 6 and 7 which carry adjustable stop screws 8 and 9 therein for the purpose of coacting with a lug 10 cast upon the outer side of the casing 1 whereby to limit the full open position of the said throttle valve 2 during operation. This throttle valve controls the outflow of atomized fuel mixture in the customary manner and need not further be described.

Referring to Fig. 3, the cylindrical throttle valve neck 11 which is somewhat smaller than the casing 1 is provided with a locking flange 12 having suitable openings 13 and 14 therein whereby the carburetor may be affixed to the connecting flange of the intake manifold of an engine in the usual manner.

In Fig. 3, the casing 1 is shown as having a connecting web 15 to which is mounted the float chamber 16 in the customary manner. The float chamber is closed by a lid 17 and carries a vertical needle valve support 18 of sufficient length to guide an interiorly mounted float stem 19 to which is affixed a float 20. The bottom end of said stem 19 is constructed in the form of a needle valve 21 and cooperates with a removable valve seat 22, which is threadedly mounted into the bottom 23 of the float chamber 16.

The float chamber lid 17 is provided with a pair of yoke supports 24 which in turn pivotally mount a pair of pivoted float control arms 26. These arms rest on the top of the float and are controlled by the rise and fall thereof through a yoke connection 27 upon the stem 19 to cause the needle valve 19-21 to release or shut off the flow of gasoline to said float chamber. The float 20 is suitably bored to permit the needle valve 19-21 to rise and fall through the center thereof so as to be under control of the float 20 as previously described.

The bottom 23 of the float chamber is provided with a downstanding bored hub 27 which is provided with a plurality of small orifices 28 drilled therethrough and is surrounded by a cast hollow union 28, the upper edges of which engage against a machined

seat 29 in said bottom 23. The union is provided with a threaded boss 30 to receive therein a suitable gasoline feed pipe 31 from any source of gasoline tank supply, not shown. The union is held in its operative position against the bottom 23 in a liquid tight manner by a screw 32 which presses against a suitable washer 33, the upper end of the said screw 32 being threadedly received into the bottom of a bore of the hub 28. As described, this constitutes the float chamber assembly.

As a means for passing fuel from the float chamber 16 to the interior of the mixing chamber casing 1, there is provided, as shown in Fig. 2, an integral cast tubular extension 34 which has a short nipple connection 35 and a compression coupling 36 whereby said nipple is attached to an integral vertical duct 37, the bottom end of which is plugged in a fluid tight manner with a plug 38, and the construction of which is more fully shown in the sectional view, Fig. 4.

In this latter view, and also Fig. 8, which is a plan view, this construction is shown as embodying in a preferably single integral casting an annular flange 39, which is bored with equi-spaced holes 40 whereby to attach this construction to the main casing 1 in assembled operative position.

This annular flange 39 and the appurtenant parts about to be described are in a single assembly, and are so adapted as to be affixed to the flange 41, located at the upper fuel passage or duct of the main casing 1. From the duct 34, the port 42 rises vertically to permit the flow of gasoline from 34, 35 upwardly until it meets the main duct 43 which is plugged on both ends as at 44 and 45 by threaded plugs. These plugs are inserted after the duct 43 has been bored therein. The upper end of the duct 42 is further provided with an inner sleeve valve or metering sleeve 46, Figs. 4, 6 and 7, the upper end of which is provided with a shoulder 47, and the lower end of which is opened as at 48, thereby to permit the upward flow of gasoline on its way to duct 42. The said sleeve 46 is further provided with an opening at one side thereof, as at 49, and registering with the inlet to the main duct 43. When the sleeve 46 is moved upwardly or downwardly, the opening from the sleeve 46 into the duct 43 is either opened in full, as shown in Fig. 7, or only partially opened as in Fig. 6, and thereby, to a certain extent constitutes a metering valve. The purpose of this particular construction is to set the carburetor so that it will supply the predetermined amount of fuel to engines of varying capacities, it being understood that in the present carburetor construction this carburetor, owing to its peculiar construction is adaptable to many engine sizes, owing to the great efficiency with which it effects fuel mixture during operation of the engine.

As a means for operating the metering sleeve 46 in the upward or downward position, as previously described, reference may be had to Fig. 2 in which the sleeve 46 is shown in outline together with its shoulder 47. A bell crank lever 48' is pivotally attached to the main casing 1 as at 49', and is mounted adjacent a cast bracket 50 into which is fitted a locked setting screw 51 which bears against the rear of the bell crank lever 48, and limits its movement to the position of the dotted lines of Fig. 2. The lower front end of the bell crank 48 is provided with an engaging teat 52 which engages in a hole in the shoulder 47 of the metering sleeve 46, so that movement of the arm 48 from the position of the full lines of Fig. 2 to the dotted lines of Fig. 2 causes the sleeve 46 to move from the position shown in Fig. 6 to the position shown in Fig. 7.

For the purpose of preventing the bell crank arm 48 from moving too freely, it is mounted on the side of the casing 1 by a locking screw 53, Fig. 2.

As a further means for varying and controlling the flow of gasoline into duct 43 in accordance with engine demands after the metering valve 46 has been set, there is provided a flattened reciprocal needle valve 54, Figs. 4, 6 and 7, which is mounted within the bore of the metering sleeve 46 in a fluid-tight manner, but capable of vertical movement therein. The upper end of said needle valve 54 is mounted within a control stud 55, the outer end of which is threaded and receives therein a thumb nut 56 whereby to lock the needle to said control stud 55. The inner end of the control stud 55, Fig. 4, is threadedly positioned in what I call a Venturi-shaped piston valve 57, the same being mounted to slidably fit within the interior of the casing 1, and which valve is reciprocal up and down within the said casing 1 during the active periods of the engine, as will be later described. In order that the stud 55 may reciprocate with the valve 57, and thereby carry the needle valve 54, as previously described, the main casing 1 is provided with a slot 58, said slot also being shown in Fig. 2. This slot is cut through the casing wall and covered against air leakage into the mixing chamber in the interior casing 1, by the side wall and contour of the piston actuated valve 57, so that when said valve is moved upwardly or downwardly, according to the state of action of the engine, the needle valve 54 is moved upwardly or downwardly according to engine demands.

By referring to Fig. 3 the piston actuated fuel control valve 57 is shown in the downward position, and in Fig. 4 it is shown in its upward or maximum position, and while in downward position the engine is either idling or at standstill, and when in the upward position is running at full speed. Due to the suction action of the pistons said valve is

lifted upwardly as in Fig. 4, or due to lack of suction action said valve moves downwardly in non-operative position, as in Fig. 3.

The movable piston valve cooperates with a conical multiple jet head 59, Figs. 3, 4 and 8 to produce the atomized fuel for the engine. As indicated in Fig. 4 this multiple jet head comprises an upper conically formed head having a central bore 67 and a neck portion 60. The lower end of the neck portion merges into 75 and forms part of the casting which also forms the duct 43. It will be further noted, as in Figs. 3 and 4, that the neck portion 60 has a hollow interior 61 whereby gasoline may be fed therein and that in Fig. 4 fuel is admitted 80 to the hollow interior by means of a duct 62 which is in connection with the duct 43. At the upper end of the annular hollow chamber 61 and upon the conical face of the multiple jet valve 59, is located a plurality of jet 85 nozzles 63 arranged concentrically to the central bore 67 which are more fully shown in Fig. 8. These jet nozzles, as will be observed, have small ports that open into the annular chamber 61, and at their outer ends are opened 90 to the interior of the Venturi-shaped valve 57 so that during maximum or near maximum engine speeds, and when the said valve 57 is lifted by the suction action of the engine, this series of multiple jet nozzles 63 are exposed 95 to the suction action of the incoming air, the path of which is indicated by the arrows A in Fig. 4. During such action of inrush of air, at other than idling speeds, the valve 57 is caused to lift away from the jet head 59, 100 and the amount of opening between the bottom of the tapering seat 64 of the said valve 57 and the tapering face of the jet head 59 is in direct proportion to the speed or suction demand of the engine. The passage of air due 105 to engine suction may, however be controlled by the amount of throttle opening of the throttle valve 2. During other than idling speeds the multiple jet nozzles 63 are exposed 110 to the high velocity air passing thereby and each of the jet nozzles 63 supply fuel to the incoming air in suitable proportions which fuel being carried upwardly within the upper portion of the chamber 1 becomes thoroughly atomized and mixed by the vortex action thus created and passes on upwardly into the engine cylinders. The tip of a jet nozzle 63 away from the head overhangs the portion of the tip opposite to it. As seen in Fig. 115 4, the edge referred to is arranged in a claw-like manner relative to the path A of the air stream.

This is also true of the jet nozzles 70. There is thus produced a jet nozzle having an outlet shaped in an oblate manner. We do not wish to be limited however to such shapes. The principle feature is the overhanging claw-like arrangement of the tip of the jet nozzles 63 and 70 relative to the paths A and C of the air stream. We attribute the uni- 120 125 130

formity of our fuel mixture to the fact that the air rushing by these overhanging portions of the tips of the jet nozzles is ripped or divided or combed, by a series of jet nozzles 5 from which are issuing streams of gasoline. This ripping and combing action, as we desire to term it, results in a very thorough mixing of the air with the gasoline. We thus obtain no columns of mixture rich in the center 10 and lean on the outer parts. We obtain a column of atomized fuel mixture having uniform air concentration throughout the entire column.

Obviously, from the foregoing description 15 the greater the speed of the engine the greater the distance the valve 57 will be lifted from its seat on the jet head 59. The greater the volume of air passing at these higher engine speeds the greater will be the amount of gasoline drawn through the jet nozzles 63 so that 20 in any range of engine speeds in which the valve 57 will occupy a proportional open position relative to the head 59 proportional gasoline is drawn into the moving air stream, thus 25 insuring a complete atomized mixture of properly proportioned gasoline and air at all times.

Owing to the angular inclination of the co-acting seat 64 of the valve 57 and the tapering face of the jet head cone 59, incoming air which enters the carburetor intake 65, Fig. 3, and which passes in the direction of the arrow B upwardly and around the jet head in the direction of the arrows A, Fig. 4, is deflected and constrained by the wire-drawing action of the Venturi-shaped passage of the piston valve 57, thereby increasing the velocity of the air by this point. The suction of the air at this increased velocity is sufficient 30 to raise the piston valve 57 in effect creating a variable venturi at the jet head position, such Venturi passage being variable as to the extent of its opening increasing or decreasing in size as the engine speeds are increased or 35 decreased.

In order to provide a fuel mixture to permit the engine to turn over at idling speeds, which are normally very low, two provisions are made herein. First provision is made for a starting mixture to start the engine when the air inlet 65 is entirely closed by means of the butterfly choke valve 66, as in Fig. 3. Air is constrainedly admitted by the said valve when starting the engine it being understood 40 that the throttle valve 2 is also closed, and thereby the small amount of air admitted, as per arrows BC, Figs. 3 and 5, is compelled to pass upwardly through the annular air passage 67. In the center of the annular air passage is mounted another constant or non-variable spray fuel nozzle or nozzle head 68, Figs. 3, 4 and 5. This latter nozzle head is connected and is integral with the fuel duct 43 and has an axial bore 45 communicating therewith, so that

in addition to fuel being admitted through duct 62 into the interior of the nozzle head cone 59, fuel is also admitted to the fixed central spray nozzle head 68. This nozzle head is provided at its upper end with a plurality of atomizing jet nozzles 70, which are more fully shown in Fig. 8. Thus, it will be seen that when the choke or priming valve 66 is closed and also the throttle valve 2, about as indicated in Fig. 5, air is constrained in 50 passing so that a small amount of air may pass through the central bore 67 and upwardly, by and around the throttle valve 2. But the gasoline in the mixture in this particular instance may not be sufficient for starting, and we have therefore provided an additional fuel supply means, and this is best indicated in Figs. 2 and 5.

By referring to Fig. 2 there is disclosed a bent pipe 71 running from the bottom of the float chamber 16 and upwardly alongside the mixing chamber casing 1 where it is suitably joined to a coupling 72 which in turn fastens the said pipe 71 to a fuel feed extension 73 which is cast to one side of and upon the neck 11 at the upper part of the carburetor. Gasoline is thus supplied to the duct 71 where it passes upwardly as in Fig. 5, and into a port nozzle 74 which extends upwardly in the duct or bore 75 of the extension 73. The upper end of the reduced nozzle 74 is controlled by a threadedly mounted needle valve 76 whereby the amount of liquid fuel passing through the port nozzle 74 is adjustably constrained.

A pair of right-angled ducts 77 and 78 are located in extension 73 and open up into the inner passage 79 controlled by the throttle valve 2 and co-operate with the bore 75 to form a by-pass so that in the event of starting the engine air passes upwardly and into port 78 as indicated by the arrow A. The air then passes upwardly in the bore 75 and passes out again above the throttle valve 2 from a small orifice extension of the port 77, thereby drawing liquid fuel up into the upper passage 79, and thence into the engine. Thus large quantities of liquid fuel, with a minimum proportion of air, is drawn into the engine for creating a rich mixture for starting purposes. However, the instant the throttle valve 2 is opened and the choke valve 66 likewise, the suction action of the incoming air is all exerted upon the piston valve 57 and the fuel passing from port 77 drops back to float level, and does not enter the carburetor until the 105 throttle valve is again tightly closed.

As a means for preventing the floating piston valve 57 from moving upwardly too quickly under the influence of a sudden opening of the throttle valve 2, and to permit gradual acceleration of the engine, notwithstanding the fact that the throttle may be suddenly fully opened, there is provided a dash pot, Fig. 3. It is connected to the said valve 57 by means of a plunger stem 81, the upper 110

end of which is threadedly connected and locked to a spider 82 which is integrally cast at the upper interior of the valve 57, the said stem extending downwardly through the bore of the fixed spray nozzle 68 and attaching to a grooved plunger piston 83 which has therein a by-pass valve 84, all of which is mounted within a dash pot housing 85 which is provided with an inclosure cap or plate 86. The plunger casing is attachedly mounted to the bottom extension of the fixed spray nozzle 68, as at 87, by means of a threaded connection, and when gasoline flows through duct 43 to the interior of the fixed spray nozzle 68, and the spray head 59, gasoline also flows downwardly into and fills the interior chamber of the dash pot 85 and the nozzle bore up to the level of the fuel in the float chamber. Thus the floating piston valve 57 must operate against the gasoline when lifted upwardly by the influence of the engine suction. To aid in quick recovery or shut-down of the floating piston valve 57 upon closing of the throttle 2 the by-pass check valve 84 is provided. When the piston valve descends the by-pass check valve 84 lifts upwardly, permitting gasoline from the underside of the piston 83 to rapidly pass to the other side of said piston, so that the dash pot permits a rapid return thereof under gravity, due to the weight of the valve 57.

The operation of the carburetor has been explained in the above description. Briefly recapitulating, if the throttle valve 2 is opened and also the check valve 66 to an extent that permits the engine to turn over, but not to run at full speed, air passes through, as previously described, in the direction of the arrows BC, and draws fuel from the central spray nozzles 68 and 70, and supplies the engine with sufficient fuel until a greater demand for power is required. On opening the throttle valve 2 to any full open position, the floating piston valve 57 is drawn off its seat by the increased suction, thereby creating a Venturi passage, increasing the velocity of the air and drawing more gasoline from the nozzles 63, 68 and 70 thus supplying a complete and full mixture to the engine at any and all speeds up to maximum speeds.

What we claim is:

1. In combination, a vertical carburetor casing; an upwardly pointed jet head disposed intermediately of the casing; a piston valve in said casing, having a Venturi passage above said head; a float chamber; a main duct disposed diametrically across the carburetor casing below the level in the float chamber and communicating with said head and provided at one end exterior to the casing with a vertical duct, the lower end portion of which communicates with and receives fuel from the float chamber; a metering sleeve fitting in said vertical duct and

provided with an open lower end and a lateral opening registerable with said main duct, whereby fuel may flow from the float chamber into the main duct and out said nozzles; said sleeve being longitudinally adjustable to meter the flow of fuel; and a reciprocal needle valve slidably in said sleeve and connected to said piston valve and provided with a flattened tapering face adjacent to said lateral opening, whereby when the piston valve is raised, the passage to the lateral opening is enlarged. 70

2. In combination, a float chamber; a vertical cylindrical carburetor casing open at its upper discharge end and having a large air inlet opening at its lower inlet end portion; a throttle valve across said discharge end; a primary valve across said inlet opening; a main fuel duct disposed diametrically across the carburetor casing below the level in the float chamber; means exterior to the casing establishing communication between said duct and the float chamber; an upwardly pointed conical multiple jet head over said duct and provided with an axial fuel bore and an outer annular fuel chamber both communicating with said main duct, and an annular air passage between said bore and annular chamber and establishing communication between the inlet and outlet ends of the casing; nozzles communicating with said bore and discharging into said passage; and nozzles arranged around said head and communicating with said chamber. 80 85

3. In combination, a carburetor casing having discharge and inlet ends; a main feed duct disposed intermediately of the casing; a head in the casing having an inner bore communicating with said main duct, and an annular air passage around said bore for communication between said ends; and lateral jet nozzles communicating with the upper end of said bore having over hanging upper claw-like tips and discharging into said passage. 100 105

4. In combination, a vertical carburetor casing; an upwardly pointed conical jet head disposed intermediately of the casing and having an annular fuel chamber therein; means supplying fuel to the chamber; a piston valve in said casing, having a Venturi passage above said head; and a series of upwardly and outwardly pointing jet nozzles arranged in an annular series on the conical face of said head and communicating with said annular chamber and provided with an over-hanging upper claw tip. 110 115

5. In combination, a vertical carburetor casing; an upwardly pointed conical jet head disposed intermediately of the casing; projecting jet nozzles on the conical face of the head and a piston valve slidably fitting in said casing and having a wide passage therethrough inwardly tapered from both ends to form a Venturi passage therein and 120 125 130

- a lower tapered seat adapted to seat and fit on said conical head and clearing all the jet nozzles exteriorly thereof when seated and over-hanging said head when the piston valve is in lowest position.
6. In combination, a vertical carburetor casing having an upper discharge end; a main feed duct disposed intermediately of the casing; an upwardly pointed head in the casing having an inner bore communicating with said main duct, nozzles in said head communicating with said bore; nozzles arranged around said head communicating with said duct; a piston valve slideable in said casing, having a Venturi passage above said head; a bottom extension bore formed on and communicating with said main duct alined with said axial bore; a dash-pot housing secured co-axially thereon; a piston in the housing having an upwardly opening check valve; and a stem smaller than the axial bore, disposed in said bores and connected to said piston and piston valve.
7. In combination, a carburetor casing; a throttle valve across the discharge end thereof; said casing having a by-pass duct communicating with the casing respectively on both sides of said valve when closed; a fuel-feed duct passing into the by-pass duct and provided with a port-nozzle in, and spaced from the walls of, the by-pass duct and discharging at a point between the ends of the by-pass duct; and an exteriorly adjustable needle adjustable into the discharge end of the port nozzle.
8. In combination, a carburetor casing having a discharge end; a throttle valve across said discharge end; said casing having a pair of by-pass ducts communicating with the casing respectively on both sides of said valve when closed, and a transverse duct passing through said by-pass ducts; a fuel-feed duct closing an end of the transverse duct and provided with a port-nozzle in, and spaced from the walls of, the transverse duct and discharging at a point between the by-pass ducts; and an exteriorly adjustable needle valve in the other end of the transverse duct and adjustable into the discharge end of the port nozzle.
9. In combination, a carburetor casing; a jet head disposed intermediately of the casing and pointed toward the discharge end; a laterally imperforate piston valve in said casing, yieldably pressed toward said head and having a Venturi passage between said head and the discharge end; a throttle valve across the discharge end of the casing; said casing having a by-pass duct having its ends communicating with the casing remote from the piston valve and respectively on both sides of said valve when closed; and a fuel-feed duct passing into the by-pass duct and provided with a port-nozzle in, and spaced from the walls of, the by-pass duct and discharging at a point between the ends of by-pass duct.
10. In combination, a vertical carburetor casing having an upper discharge end and a lower inlet end; a throttle valve across said discharge end; an upwardly pointed jet head disposed intermediately of the casing; a float chamber communicating with said head; a piston valve in said casing, having a Venturi passage above said head; said casing being formed with a pair of ducts communicating with the outlet end of the casing at right angles thereto above the highest position of the piston valve, respectively above and below the throttle valve when in closed position, and a transverse duct passing transversely through said right angled ducts; a duct communicating with the float chamber and fitting in said transverse duct and provided with a port nozzle in, and spaced from the walls of said transverse duct and entering below the lower right angled duct and extending beyond said lower duct to a point about half way between the right angled ducts; whereby fuel mixture by-passing through the right angled ducts exerts an induction action upon said port; and a needle valve comprising an exteriorly adjustable threaded plug adjustably screwed in the upper end of the transverse duct and having a point adjustably disposable in or near the discharge end of the port nozzle.
11. In combination, a vertical carburetor casing having discharge and inlet ends; a duct provided with a fuel passage laterally communicating with the duct; means supplying fuel to said passage; an upwardly pointed jet head within the casing and having jet nozzles communicating with said duct; a piston valve slideable in said casing, and having a Venturi passage therethrough disposed over said head; a valve member slideable in said fuel passage and connected to said piston valve and adapted to cover or vary the passage to the duct; a lever fulcrumed on said casing and connected to said member for adjusting the member; an adjustable stop for said lever; and means for locking the lever.
12. In combination, a carburetor casing; a duct provided with a fuel passage; means supplying fuel to said passage; a jet head within the casing communicating with said duct; a longitudinally adjustable metering sleeve fitting in said fuel passage and adapted to cover said duct; and a needle valve stem slideable in said sleeve and having its active end adjacent to said duct to vary the passage thereto.
13. In combination, a carburetor casing; a duct provided with a fuel passage; means supplying fuel to said passage; a jet head within the casing communicating with said duct; a valve movable in said casing between said head and the discharge end of the casing; a longitudinally adjustable metering sleeve fitting in said fuel passage and adapt-

ed to cover said duct; and a needle valve stem
slidable in said sleeve and connected to said
piston valve and having one end adjacent to
said duct to vary the passage thereto.

5 14. In combination, a mixing casing having
an air passage therein; and a fuel jet
nozzle discharging into said passage and hav-
ing a projecting pointed tip between the nozzle
outlet and the discharge end of the pas-
10 sage, said tip extending laterally further into
said passage than does said outlet thereby
to project into the stream of discharged fuel
to divide and mix the fuel and air.

15 15. In combination, a carburetor having an
air passage therein; and jet nozzles discharg-
ing laterally approximately perpendicularly
into said passage and having over-hanging
claw-like tips projecting laterally further
20 into the passage than does the orifice of the
nozzle and disposed between the orifice and
the discharge end of the passage.

25 16. In combination, a carburetor casing; a
conical jet head disposed intermediately of
the casing and pointed toward the discharge
end; and jet nozzles on said head discharg-
ing and having projecting tips between the
30 nozzle orifice and the discharge end of the
casing, said tips projecting further from the
conical face of the head than do the orifices
of the nozzles.

35 17. In combination, a vertical carburetor
casing; an upwardly pointed conical jet head
disposed intermediately of the casing; up-
wardly and outwardly pointing jet nozzles
arranged on the conical face of said head and
discharging perpendicularly thereto, and
each provided with an over-hanging upper-
claw tip between the nozzle orifice and the
discharge end of the casing.

40 40 Signed at New York, in the county of New
York and State of New York, this 17th day
of November, A. D. 1927.
